UNITED STATES PATENT OFFICE.

FELIX B. MILLER, OF ATTLEBORO, MASSACHUSETTS, ASSIGNOR TO FILLWIK COMPANY, OF ATTLEBORO, MASSACHUSETTS, A CORPORATION OF MASSACHUSETTS.

CONTAINER.

Application filed February 20, 1928. Serial No. 255,614.

My invention relates to containers and refers particularly to containers suitable for use with a plurality of materials.

My device is particularly adapted for a plurality of toilet preparations such as powder compacts and rouge.

The usual toilet preparation set contains a larger white compact, a smaller rouge compact and a rouge paste and the particular form of my device shown and described is adapted for these toilet preparations, but it is evident that other preparations and materials may be employed.

It is desirable that a mirror surface be exposed when any one of the contents is being used.

It is also desirable that the container be as small and compact as possible.

It is further advantageous that a desired material be easily exposed for use and that the other materials be retained from movement which would dislodge them from their positions.

The above, and other, desirable features are possessed by my device as will be evident upon a consideration of my specification and the accompanying drawings.

In the accompanying drawings illustrating one form of my device similar parts are designated by similar numerals.

Figure 1 is a perspective view of one form of my device in closed position.

Figure 2 is an enlarged top plan view of my device, in open position, to expose the contents of the top member, partly broken away for clearness of description.

Figure 3 is a section through the line 3—3 of Figure 2.

Figure 4 is a perspective view of the compact tray of the top member.

Figure 5 is a top plan view of my device in open position to expose the contents of the bottom member.

Figure 6 is a section through the line 6—6 of Figure 5.

Figure 7 is a perspective view of the rouge tray of the bottom member.

Figure 8 is a side view showing the various elements in extended position.

The particular form of the device of my invention illustrated in the accompanying drawing comprises a top receptacle and a bottom receptacle hingedly attached to each other by a mirror carrying member.

The top member comprises the bottom 10,

the side flanges 11 and 12, the front flange 13 and the back flange 14. The sides 11 and 12 have the extended flanges 15, 15, positioned toward the front flange 13 for purposes of easy opening of the device. The central portion of the front end 13 has an extended hook 16.

The bottom member comprises the bottom 17, the side flanges 18 and 19, the front flange 20 and the back flange 21. The sides 18 and 19 have the extended flanges 22, 22 positioned toward the back flange 21 for purposes of easy opening of the device. The central portion of the front end 20 has an extended hook 23.

The back flanges 14 and 21 are hingedly attached to each other by means of the double faced metallic mirror member 24.

The mirror member 24 has an opening 25 capable of receiving the hook-catch 16 of the top member, and an opening 26 capable of receiving the hook-catch 23 of the bottom member.

The pin 27 of the bottom member and the pin 28 of the top member, act as thumb pieces 80 to facilitate the opening of the device.

The top member contains the compact tray 29 carrying the compact 30 and the powder puff 31.

The bottom member contains the compact 32 carrying the compact 33 and the powder puff 34 and also carries the rouge container 35 having the hinged cover 36 and the rouge 37.

The top member and the bottom member 90 are held in frictional contact with each other when the device is in closed position.

In order to connect the bottom member, the top member and the mirror member to form my device, opposite end portions 38 and 39 of the mirror member 24 are turned over to form a hinge portion; end portions 40, 40 of the top member are turned over to form a hinge portion and end portions 41, 41, of the bottom member are turned over to form a hinge portion, a pintle 42 is passed through the hinge portions 38, 40, 40 and a pintle 43 is passed through the hinge portions 39, 41, 41. It will thus be seen that integral turned portions of the mirror member and the bottom member form a hinge and that integral turned portions of the mirror member and the top member form a hinge, the bottom member and the top member being positioned upon opposite sides of the mirror member. It 110

will be noted that this construction allows the mirror member to be positioned within the sides of the top member and the bottom member when the device is closed, thus causing the sides of the top member and bottom member to abut upon each other.

I have referred to two elements of the illustrated device as "top member" and "bottom member", simply as a means for clearly describing my device.

The operation of my device is as follows:—

When it is desired to employ the top compact 30, the top member is held in a horizontal position and the bottom member is opened upon its hinge, the hook-catch 16 being released from the opening 25, and the hook-catch 23 being retained within the opening 26. The user, therefore, has the compact 30 exposed for use with the mirror member covering the bottom member and having an exposed mirror surface.

When it is desired to employ the bottom compact 33 and gain access to the rouge 37, the bottom member is held in a horizontal position and the top member is opened upon its hinge, the hook-catch 23 being released from the opening 26 and the hook-catch 16 being retained within the opening 25. The user, therefore, has access to the compact 33 and the rouge 37, with the mirror member covering the top member exposing a mirror surface.

It will thus be seen that the user can gain access to the contents of either the bottom member or the top member by simply holding the desired member stationary and moving the other member, and that in each case the undesired member is covered by the mirror member with a mirror surface exposed.

While I have shown my device as being used as a container for toilet articles, it may be employed for containing other articles, for instance one member may contain cigarettes and the other member may contain toilet articles.

The device of my invention, therefore, presents an extremely compact container for a plurality of contents some of which are readily exposed for use while retaining the undesired materials from movement and contact and disclosing a mirror.

I do not limit myself to the particular size, shape, number or arrangement of parts as illustrated and described as these are given simply as a means for clearly describing the device of my invention.

What I claim is:—

1. In a toilet preparation container, in combination, a double faced metallic mirror having turned hinge portions at opposite ends thereof, a top container having integral turned hinge portions hingedly attached to the hinge portion of one side of the mirror and a bottom container having integral turned hinge portions hingedly attached to the hinge portion of the other side of the

mirror, the mirror being capable of placement between the top container and the bottom container when the device is in closed position.

2. In a toilet preparation container, in combination, a double faced metallic mirror having turned hinge portions at opposite ends thereof, a top container having integral turned hinge portions hingedly attached to the hinge portion of one side of the mirror, a bottom container having integral turned hinge portions hingedly attached to the hinge portion of the other side of the mirror, the mirror being capable of placement between the top container and the bottom container when the device is in closed position and so positioned that the edges of the top container and of the bottom container abut upon each other when the device is closed.

3. In a toilet preparation container, in combination, a double faced metallic mirror, a top container hingedly attached to one edge of the mirror and a bottom container hingedly attached to the opposite edge of the mirror, the elements being so positioned that the mirror will be completely within the device when the device is in closed position, the edges of the two containers abutting upon each other.

4. In a toilet preparation container, in combination, a double faced metallic mirror, a top container and a bottom container hingedly attached to opposite ends of the mirror, said mirror acting as a cover respectively for the top container and the bottom container when the device is in open position, the mirror being completely within the closed device.

5. In a toilet preparation container, in combination, a double faced metallic mirror, a top container and a bottom container hingedly attached to opposite ends of the mirror, said mirror acting as a cover respectively for the top container and the bottom container when the device is in open position, the mirror being completely within the closed device, the edges of the closed container abutting upon each other.

6. In a toilet preparation container, in combination, a double faced metallic mirror having turned hinge portions at opposite ends thereof, a top container having integral turned hinge portions hingedly attached to the hinge portion of one side of the mirror, a bottom container having integral turned hinge portions hingedly attached to the hinge portion of the other side of the mirror, the mirror being capable of placement between the top container and the bottom container when the device is in closed position and a plurality of toilet preparation carriers within the containers.

7. In a toilet preparation container, in combination, a double faced metallic mirror, a top container hingedly attached to one

edge of the mirror, a bottom container hingedly attached to the opposite edge of the mirror, the elements being so positioned that the mirror will be completely within the device when the device is in closed position, the edges of the two containers abutting upon each other and a plurality of toilet preparation carriers within the containers.

8. In a toilet preparation container, in combination, a double faced metallic mirror, a top container, a bottom container hingedly attached to opposite ends of the mirror, said

mirror acting as a cover respectively for the top container and the bottom container when the device is in open position, the mirror being completely within the closed device, the edges of the closed containers abutting upon each other and a plurality of toilet preparation carriers within the containers.

Signed at Attleboro, in the county of Bristol and State of Massachusetts, this 14 day of February, 1928.

FELIX B. MILLER.
